Primary Examiner — John R Yeh(74) *Attorney, Agent, or Firm* — Daniel Polonenko(57) **CLAIM**

The ornamental design for a carpet fringe comb, as shown and described.

DESCRIPTION

FIG. 1 is a perspective view for a carpet fringe comb showing my new design;

FIG. 2 is a front elevation view thereof;

FIG. 3 is a rear elevation view thereof;

FIG. 4 is a top plan view thereof;

FIG. 5 is a bottom plan view thereof; and,

FIG. 6 is a side elevation view thereof.

The broken lines in the figures illustrate portions of the carpet fringe comb which form no part of the claimed design.
